UNITED STATES PATENT OFFICE.

HENRY PEETERS, OF WARCOING, BELGIUM.

TYPEWRITER.

Application filed February 20, 1924, Serial No. 694,077, and in Belgium December 21, 1923.

This invention relates to improvements in typewriters and more particularly to devices intended to move the paper holding carriage in both directions.

5 This invention is applicable to typewriters in which the carriage is temporarily held in a given position before reaching the end of its travel, by means of an escapement mechanism, the release of which is controlled by 10 hand or by the depression of a key.

The device according to the invention is applicable to machines for printing characters placed normally one after another from left to right, and also, as is usual in certain 15 oriental languages, from right to left. By "movement of the carriage in the direction permitting writing," is therefore understood the automatic movement of the carriage under the action of a suitable spring after the 20 typing of a given character, whilst by "return movement of the carriage" is understood the movement in the opposite direction under the action of a lever operated by hand.

25 The invention is applicable to typewriters in which the carriage moves automatically in the direction of writing, after the disengagement of the escapement mechanism, by a control spring element, and in the return 30 direction by a control element connected to the carriage by means of a pinion and a rack.

According to the invention this control element is given a motion of translation in a direction parallel with the carriage and is 35 so connected that the extent of movement of one of the elements is equal to that of the other. For this purpose, the above said pinion is mounted on an axle which carries a second pinion meshing with a second rack.

40 The latter is connected to an oscillating frame carrying the control element, by means of a rod pivoted at its ends. The length and the relative positions of the rod and of the frame are such that the translatory movement of the control element is 45 transmitted with an equal amplitude to the carriage, and vice versa.

The countershaft also carries a helical spring which surrounds it, and the action of 50 which produces the advance of the carriage in the direction permitting writing, the said spring being set when the carriage is moved in the opposite direction.

The said control part comprises two rods with handles, said rods being coupled together in order to be moved together during the displacement of the carriage, while being able to rotate independently, one of the rods controlling the escapement mechanism for the displacement of the carriage in the direction of writing, and the other moving the carriage in the return direction, while acting on the line-spacing mechanism.

55 The spring which exercises a constant pull on the carriage in a given direction, produces an automatic movement of the said carriage so as to allow writing in either direction, with the assistance of a reversing mechanism. This spring produces the rotation of two toothed wheels rotating in opposite directions and carried by the same countershaft as the spring, one of the said wheels being brought into engagement with a toothed rack provided on the carriage.

60 According to a preferable arrangement, 70 one and the same rack may be moved relatively to the carriage so as to bring it into contact with one or the other of the toothed wheels rotating in opposite directions.

75 The movement of the rack relatively to the carriage produces at the same time the disengagement thereof corresponding to the direction of movement to be no longer utilized, and the engagement of the escapement mechanism corresponding to the direction of 80 movement to be adopted.

85 To that end, the escapement mechanism drives through a toothed pinion, a rack provided on the carriage, and in order to allow the escapement to be controlled in accordance with the two directions of travelling of the carriage, according to the invention is provided a longitudinal frame, the two large inner faces of which have the form of a rack, and either of them may be brought into engagement with the pinion driven by the escapement.

90 Two constructions according to the invention are illustrated by way of example in the accompanying drawings.

100 In the said drawings,

105 Figure 1 is a perspective view of the device moving the carriage in the two directions, applied to a machine in which is used only the direction of travelling allowing writing from left to right;

Figure 2 is a rear view of the mechanism mounted on a carriage which allows writing from left to right, or from right to left;

Figure 3 is a view looking towards the right, in section on the line 3—3 of Figure 2;

Figure 4 is a view similar to that of Figure 3, showing the position of the elements after the reversing gear has been operated;

Figure 5 is a perspective view of a detail of the mechanism shown in Figures 2-4.

In the said figures, the same parts are marked with the same reference figures, which correspond also to those of the concurrent applications which relates to the general arrangement of the typewriter, to the escapement mechanism of the carriage and to the return key.

The carriage 60 which carries the paper by means of the pairs of driving rollers 63—64 and 65—66, travels by means of its rollers 61 on the bed 62 of the typewriter. This carriage 60 has a rack 103 which engages with a toothed wheel 105 mounted on a vertical spindle 102. The said spindle has at its lower end a pinion 107 which meshes with a rack 100 adjustable in its longitudinal direction between the guides 112. The movements to the left and to the right are controlled by means of the oscillating frame 113—114 pivoted about fixed pins 115 and connected to the rack 100 by the rod 116 pivoted at its ends.

The length and the relative positions of the elements 113 of the frame 113—114 and of the rod 116, are calculated so that the respective angular movements of the elements 113 and 116 take place in the opposite directions under the action of the lever 106—117, in order to make the linear movements of the system uniform at any moment of its travel.

The said lever 106—117 is constituted by two parallel rods connected together by collars 118—119 so that both levers may be moved simultaneously and at the same time may be turned individually in their supports 119. The ends of the said rods carrying the handles 120 and 121, project in front of the machine.

In that way, the longitudinal movement of the lever 106—107 is utilized for measuring the travel of the carriage and also intervenes in the operation of the return key, as described in a separate concurrent application.

In order to move the carriage in the direction of its return, that is to say from left to right, the rods 106, 117 are caused to swing to the right and by inclining the handle 121, the rod 117 acts on a horizontal bar 122 through a roller 125 supported by two arms 126, keyed to the rod 117 and rolling along the bar 122 which is raised by pivoting about fixed pins 123 until it comes in contact with a stop 130, the said bar controlling by means

of the rod 124 the line-spacing mechanism 70 shown diagrammatically. The said line-spacing mechanism is set, as is done in known typewriters, so as to control by an action on the rod 117, the driving of the paper to one or two lines spaces, or it may be disengaged from the action of the rod 117.

To move the carriage in the direction of writing, that is to say from right to left, it is sufficient to disengage the escapement mechanism which holds the carriage in opposition to the action of the spring which drives it automatically after typing each letter.

To that end, the rod 106 has at its end an easily accessible handle 120 which on being turned to the left drives the rod 106 carrying a roller 127 supported by the arms 128. This roller depresses the pivoted horizontal bar 129 swinging about the fixed pins 123 until it comes in contact with the stop 125'. The bar 129 lowers the lever 131 pivoted at one end about the pivot pin 132 and acting with its other end on the escapement mechanism (not shown) which controls the carriage by means of the pinion 133 meshing with the horizontal rack 134. The said pinion is free during the return travel of the carriage, as is the case in the ordinary typewriters.

The spring 101, the tension of which acts on the carriage so as to move it automatically in the direction of writing, is wound helically about the countershaft 101. One end of the said spring is secured to the collar 135 provided on the bed 62, and the other end is secured to the spindle 102 carrying the toothed wheel 105. This spring is set during the movement of the carriage from left to right, by means of the system of levers 117—116, the rack 100 and the pinion 107.

The rods 106 and 117 are constituted each by two telescope parts in order that their end carrying a pointer 136 moves, during the pivoting about the pins 115, in a slot 137 provided in front of a graduated scale 138 measuring the travel of the carriage.

In Figures 2-4, this method of controlling the carriage is shown, applied to a typewriter allowing writing in both directions, that is to say from left to right or in the usual direction, and from right to left.

To that end, the rack 103 secured to the carriage 60, may be moved relatively to the latter by sliding in guides 139 under the action of a cam 140 resting on a point of the carriage.

The main spring 101 acts through a suitable reversing mechanism on the said rack, that is to say, by bringing it into contact with one of the toothed wheels 105 or 141 rotating in opposite directions, the former of which corresponds to the travel for ordinary writing, and the second one to the travel in the opposite direction. The con-

nection between the spring and the wheel 141 is effected by the toothed wheels 105, 142 and 143. As the pinion 133 of the escapement mechanism holds the carriage 5 only when rotating in one direction, the said rack 134 which engages with the pinion 133, is formed into an inner face of a longitudinal frame 144 secured to the rack 103 and moving with the latter relatively to the carriage. The opposite inner face 145 of the said frame is also formed into a rack. The first rack 134 meshes with the pinion 133 during the movement in the direction of ordinary writing, and the second one, 145, 10 during the movement in the opposite direction.

Figure 5 shows in detail the arrangement of the ends of the rods 106-117 used in the construction described with reference to 20 Figures 2-4. The rods 106-117 are arranged above each other, and the rod 106 carries two rollers 125 and 125' for the purpose of raising, on the handle 121 being turned either to the left or to the right, the 25 said bar 122 during its movement in one of these directions.

In that way, with one and the same handle 121, it is possible to operate the line spacing mechanism by rotating the handle 30 121—either clockwise or counter-clockwise, and nevertheless the carriage return is always effected by swinging the rods 106, 117 to the left in the direction corresponding to the movement, produces therefore in 25 either of the two directions the operation of the line spacing mechanism.

The same applies to the rod 106 carrying the two rollers 127 and 127', so that the handle 120 may be turned either to the right 40 or to the left in order to lower the bar 129.

By arranging thus two rollers at the ends of the rods 106 and 117, the handles 120 and 121 may be turned in the direction of movement of the roller, the corresponding auxiliary mechanism being operated at the same time. It must be pointed out, however, that 45 one roller 125 or 127 may also be sufficient, but in that case the handle is turned in the same direction, for instance to the left, the carriage moving to the left or to the right.

What I claim as my invention and desire to secure by Letters Patent is:

1. In a typewriter in which the carriage carrying the paper is held in a given position by means of an escapement mechanism, the disengagement of which is controlled by hand or by the depression of a key, a carriage which can be moved in the return direction by a control part acting on the carriage, by means of a toothed wheel, meshing with a rack secured to the carriage and means for producing a rectilinear displacement of said control part in a direction parallel to the motion of the carriage.

2. In a typewriter in which the carriage

carrying the paper is held in a given position by means of an escapement mechanism, the disengagement of which is controlled by hand or by the depression of a key, a carriage which can be moved in the return 70 direction by a control part acting on the carriage, by means of a toothed wheel, meshing with a rack secured to the carriage, the control part being connected to the actuating means of the toothed wheel by two rods 75 composed of two parts sliding in each other so that their ends bearing a mark can be moved along a rectilinear scale measuring the displacement of the carriage in a direction parallel to its motion. 80

3. In a typewriter in which the carriage carrying the paper is held in a given position by means of an escapement mechanism, the disengagement of which is controlled by hand or by the depression of a key, a carriage which can be moved in the return 25 direction by a control part acting on the carriage by means of a toothed wheel mounted on a countershaft and meshing with a rack secured to the carriage, a second toothed wheel mounted on the countershaft and meshing with a second rack, an oscillating frame supporting the control part and connected to said second rack by a rod pivoted at its ends, the length and the relative positions, of the frame and the rod being such, that the translation motion of the control part is equally transmitted to that of the carriage and vice versa. 90

4. In a typewriter in which the carriage carrying the paper is held in a given position by means of an escapement mechanism, the disengagement of which is controlled by hand or by the depression of a key, a carriage which can be moved in either direction by a control part, a rack secured to the carriage, a toothed wheel mounted on a countershaft and meshing with said rack, a second toothed wheel mounted on the countershaft and meshing with a rack operated by said control part through a system of rods, and a helical spring carried by the countershaft, the tension of which produces the advance of the carriage in the direction 100 permitting writing, after the disengagement of the escapement mechanism due to the depression of a key. 105

5. In a typewriter in which the carriage carrying the paper is held in a given position by means of an escapement mechanism, the disengagement of which is controlled by hand or by the depression of a key, a carriage which can be moved in either direction by a control part, a rack secured to the carriage, a toothed wheel mounted on a countershaft and meshing with said rack, a second toothed wheel mounted on the countershaft and meshing with a rack operated by said control part through a system of rods, and a helical spring carried by the countershaft, 110 115 120 125 130

the tension of which produces the advance of the carriage in the direction permitting writing, after the disengagement of the escapement mechanism due to the depression of a key, the said spring being set by the carriage being moved in the opposite direction.

6. In a typewriter in which the carriage carrying the paper is held in a given position by means of an escapement mechanism, the disengagement of which is controlled by hand or by the depression of a key, a carriage which can be moved in either direction after the disengagement of the escapement mechanism by means of a control part comprising

15 two rods with handles, said rods being coupled together in order to be moved together during the displacement of the carriage, while being able to rotate independently, one of the rods being intended to control 20 the escapement for the displacement of the carriage in the direction of writing and the other being intended for moving the carriage, in the return direction while acting ultimately in the line spacing mechanism.

7. In a typewriter in which the carriage carrying the paper is held in a given position by means of an escapement mechanism, the disengagement of which is controlled by hand or by the depression of a key, a carriage which can be moved in either direction after the disengagement of the escapement mechanism by means of a control part, the movement of the carriage being brought about by the action of a spring which constantly exercises a pull on it in a given direction, said spring acting on a countershaft which carries two toothed wheels rotating in opposite directions, one or the other of the said wheels being caused to mesh with a rack provided on the carriage.

8. In a typewriter in which the carriage carrying the paper is held in a given position by means of an escapement mechanism, the disengagement of which is controlled by hand or by the depression of a key, a car-

riage which can be moved in either direction after the disengagement of the escapement mechanism by means of a control part, the movement of the carriage being brought about by the action of a spring which constantly exercises a pull on it in a given direction, said spring producing the rotation of two toothed wheels rotating in opposite directions, one or the other of the said wheels being caused to mesh with a rack provided on the carriage, the displacement of said rack relatively to the carriage by reversing the direction of movement, producing simultaneously the disengagement of the escapement mechanism corresponding to the direction of travelling to be no longer utilized and the reengagement of said escapement mechanism corresponding to the direction of movement to be adopted.

9. A typewriter in which the carriage carrying the paper is held in a given position by means of an escapement mechanism, the disengagement of which is controlled by hand or by the depression of a key, a carriage which can be moved in either direction after the disengagement of the escapement mechanism by means of a control part, the movement of the carriage being brought about by the action of a spring which constantly exercises a pull on it in a given direction, said spring being adapted to produce the automatic movement of the carriage in both directions, by acting on it through a reversing mechanism, the escapement mechanism acting through a toothed pinion on a rack provided on the carriage, a second adjustable rack secured to the carriage and meshing with aforesaid reversing mechanism, said rack carrying a longitudinal frame, the two large sides of which have the shape of racks, either one or the other of these sides being brought into engagement with the pinion driven by the escapement.

In testimony whereof I affix my signature.
HENRY PEETERS.
